UNITED STATES PATENT OFFICE

168,375

WALL ORNAMENT

Timothy T. Ross, Cleveland, Ohio

Application January 25, 1952, Serial No. 18,219

Term of patent 7 years

(Cl. D33—3)

To all whom it may concern:

Be it known that I, Timothy T. Ross, a citizen of the United States, residing at Cleveland, in the county of Cuyahoga, and State of Ohio, have invented a new, original, and ornamental Design for a Wall Ornament, of which the following is a specification, reference being had to the accompanying drawing, forming part thereof.

I claim:

The ornamental design for a wall ornament, as shown.

TIMOTHY T. ROSS.
